UNITED STATES PATENT OFFICE.

HARRY HOWE, OF BELLEVUE, PENNSYLVANIA, ASSIGNOR TO PRESSED STEEL CAR COMPANY, OF PITTSBURGH, PENNSYLVANIA, A CORPORATION OF NEW JERSEY.

METALLIC ANNEALING-BOX.

1,360,639.

Specification of Letters Patent. Patented Nov. 30, 1920.

Application filed August 5, 1920. Serial No. 401,459.

To all whom it may concern:

Be it known that I, HARRY HOWE, a citizen of the United States, residing in Bellevue, in the county of Allegheny and State of Pennsylvania, have invented certain new and useful Improvements in Metallic Annealing-Boxes, of which the following is a specification.

An object of the present invention is to provide an air-tight metallic annealing box which can be easily and cheaply manufactured, and which will be light in weight and strong, and capable of resisting the tendency to collapse under the intense heat to which such annealing boxes are subjected.

Another object of the invention is to provide an annealing box which is constructed of a plurality of sheet metal parts and which have their adjacent edge portions welded to each other.

Referring to the accompanying drawings in which like reference characters refer to like parts, Figure 1, is a plan view of an annealing box constructed in accordance with the invention; Fig. 2 is a side elevational view and Fig. 3 is an end elevational view of the same; and Figs. 4, 5, and 6 show similar views of a modification of the invention.

Referring now in detail to the drawings, reference characters 1 and 2 indicate the end walls of the box which are preferably identical in form. Each end wall consists of an end wall proper 3, and an upper portion 4, forming a part of the roof of the box, the lower portion 3 being provided with flanges 5 at its sides, and the upper portion 4 being provided with similar flanges 6 which converge and meet each other. The side walls 7 and 8 are preferably identical in form each having sides proper or vertical portions 9 and upper portions 10, which latter portions form portions of the roof of the box. These are provided with flanges 11 on their side portions and the upper portion of these side walls are provided with converging flanges 12, and a flange 13 extending preferably along the longitudinal center line of the box. The flanges 5 and 11 contact with each other and are electrically welded together at spots throughout their lengths, as also are the

flanges 6 and 12 as well as the two flanges 13. To render the box air-tight the joints between the various flanges referred to are sealed throughout their lengths by welding 55 them together, which welding may be done by means of electricity or by any other suitable or convenient means.

It will here be noted that the crown or top of the box when constructed in accordance with the invention is of a curved or arched form and hence is well adapted to withstand collapse due to the high degree of heat to which the box is subjected.

Figs. 4, 5, and 6 show a modification of the 65 invention in which the end walls 14 are preferably identical in form each having a flat portion 15 provided with flanges 16 which are continuous around three sides of the end. The side walls 17 are also preferably identi- 70 cal in form, each side wall forming not only the side proper 18 of the box but also half of the crown 19 of the box. The upper or crown portion 18 of the side wall is provided with an edge flange 20 which contacts with 75 and is welded to a similar flange on the edge of the plate forming the other side of the box. It will be seen from the drawings that the end portions of the side walls contact with the flanges 16 of the end walls, and may be welded thereto by electricity or any other suitable means. Lugs 21 may be secured to the ends of the box for lifting purposes, as shown in the drawings.

Having thus described the invention what 85 I claim as new and desire to secure by Letters Patent is:—

1. An annealing box comprising sides and ends, said sides and ends being substantially identical in shape, portions of said sides and ends forming portions of the roof of the box and flanges for securing together said sides and ends.

2. An annealing box comprising sides and ends, portions of said sides and ends forming portions of the roof of the box, said portions being connected together by flanges which converge toward the center of the box.

3. An annealing box comprising side and end walls, said side and end walls having substantially V-shaped upper portions which form portions of the roof of the box and

flanges on said V-shaped portions for securing them to each other.

4. An annealing box comprising side and end walls, said end walls having upper portions which form a portion of the roof of the box and flanges for securing said ends and sides together.

In testimony whereof I affix my signature in the presence of two witnesses.

HARRY HOWE.
